UNITED STATES PATENT OFFICE.

WIGHTMAN ERSKINE, OF BURLINGTON, IOWA.

DESIGN FOR A HEAD FOR CLOTHES-RACKS.

SPECIFICATION forming part of Design No. 31,937, dated December 5, 1899.

Application filed November 11, 1899. Serial No. 736,702. Term of patent 14 years.

To all whom it may concern:

Be it known that I, WIGHTMAN ERSKINE, a citizen of the United States, residing at Burlington, in the county of Des Moines and State 5 of Iowa, have invented and produced a new and original Design for a Head for a Clothes-Rack, of which the following is a specification.

The invention relates to a new and original design for a head for a clothes-rack; and it 10 has for its object to provide a design of this character which will be both ornamental and useful.

The essential feature of the design resides in an annular dish-shaped head consisting of 15 an annular bottom, inner and outer concentric walls diverging upwardly, and an arched or dome-shaped top extending over the space inclosed by the inner wall, said inner and outer walls being provided with slots, the 20 outer slots being approximately L-shaped and terminating short of the upper edges of the outer wall to provide a continuous rim.

In the drawings, Figure 1 is a sectional perspective view of a head, showing my new and 25 original design. Fig. 2 is a plan view.

Referring to the drawings, 1 designates a head consisting of an annular dish-shaped body and provided with inner and outer walls 2 and 3, concentric with each other and di-

verging upwardly. The outer wall is inclined 30 outward slightly and is provided with a continuous rim 4, from which extend slots 5, which are substantially L-shaped. The inner and outer walls are connected by an annular bottom 6, and the slots 5 extend from 35 the rim 4 downward and inward, and terminate short of the center of the bottom.

The inner wall 2 inclines toward the center of the head, which is provided with a central dome-shaped top 7, extending upward and inward from the inner wall and arranged over the space inclosed by the same. The dome-shaped top 7, which forms a continuation of the inner wall 2, presents an outer convex face and an inner concave face, and it has a 45 central opening 8. The inner wall 2 is provided with an annular series of slots 9, which are straight.

What is claimed is—

The design for a head as herein shown and 50 described.

In testimony that I claim the foregoing as my own I have hereto affixed my signature in the presence of two witnesses.

WIGHTMAN ERSKINE.
